UNITED STATES PATENT OFFICE.

WALTER F. MOORE, OF FAYETTEVILLE, TENNESSEE.

ICE-SAW.

1,115,087.

Specification of Letters Patent. Patented Oct. 27, 1914.

Application filed May 29, 1914. Serial No. 841,917.

To all whom it may concern:

Be it known that I, WALTER F. MOORE, a citizen of the United States of America, residing at Fayetteville, in the county of Lincoln and State of Tennessee, have invented 5 certain new and useful Improvements in Ice-Saws, of which the following is a specification, reference being had therein to the accompanying drawing.

10 This invention relates to an ice saw and has special reference to a saw which is adapted to be carried by the body of a wagon for cutting ice into desired quantities when the same is being removed from the 15 wagon body.

Another object of this invention is the production of a saw for the purpose specified which is adapted to be operated by the rotation of the supporting wheels and which 20 is so formed as to be easily shifted so as to remain inoperative when desired.

With these and other objects in view this invention consists of certain novel combinations, constructions and arrangements of 25 parts as will be hereinafter fully described and claimed.

In the accompanying drawings:—Figure 1 is a side elevation of a wagon showing the saw carried thereby in a position for use. 30 Fig. 2 is a bottom plan view of the rear portion of a wagon showing the saw in position. Fig. 3 is a rear elevation of a wagon the saw being shown in position for use. Fig. 4 is a longitudinal section through the 35 rear portion of a wagon showing the manner in which the saw operates. Fig. 5 is a section taken on the line 5—5 of Fig. 1. Fig. 6 is a perspective view of the operating lever which is adapted to shift the saw.

40 Fig. 7 is a section taken on the line 7—7 of Fig. 2. Fig. 8 is a detailed perspective view of a portion of the wagon body showing the ice supported thereby. Fig. 9 is a section taken on the line 9—9 of Fig. 5. Fig. 10 is a section taken on the line 10—10 of Fig. 4.

45 Referring to the accompanying drawings by numerals 1 designates the bottom of the wagon having the sides 2 and 3, this body which is formed by the bottom 1 and sides 50 2 and 3 is supported by the usual wheels 4 and 5. The bottom 1 is provided adjacent

its rear portion with a longitudinally extending slot 6 through which the circular saw 7 normally extends. This saw 7 is keyed to the shaft 8 which passes through 55 the sleeve 9. Upon each end of the sleeve 9 there is threaded a hollow collar 10 in which there is provided a plurality of bearing rollers 11 so as to cause the shaft 8 to freely rotate since these roller bearings 11 will carry 60 the greater portion of the weight of the saw and the shaft. The sleeve 9 passes through the yokes 12 and these yokes 12 curve slightly toward their lower portions as clearly disclosed in Fig. 7. The upper portions of these yokes are provided with the lateral projections 13 through which the securing members 14 pass for fixedly securing the yokes in engagement with the bottom 1 of the wagon. 70

For the purpose of supporting the sleeve 9 and shaft 8 adjacent the under surface of the bottom 1 of the wagon, the keys 15 may be passed transversely through the yokes 12 so as to allow the sleeve 9 to rest thereon 75 when the saw is in use. To the end of the shaft 8 opposite to that upon which the circular saw 7 is supported there is provided a pinion 16 which is held fixedly upon the shaft. This pinion is adapted to be engaged by the 80 internal gear wheel 17 which is secured to one of the rear wheels 5 by means of the U-shaped bolts 18 passing around the spokes 19 of the wheel 5 and through the internal gear wheel 17 at which time the retaining nuts 85 20 are placed thereon. This wheel 17 is provided with the teeth formed upon its inner periphery and is provided with the integral lugs 21 for holding the same in spaced relation to the spokes 19. 90

It will be seen from the foregoing description that as the wagon is in motion and the rear wheels are rotated the internal gear wheel 17 will drive the pinion 16 which will in turn impart rotary motion to the circular 95 saw 7 by means of the shaft 8. The ice which is in the body of the wagon may be pushed into engagement with the circular saw 7 and since the same is rotated the ice may be cut into blocks of any desired size 100 and quantity. It may be desirable, however, to place the circular saw in an inoperative

position and therefore the arm 22 having a hollow head 23 may be positioned upon the sleeve 9. This arm 22 is adapted to pass upwardly through the slot 24 so as to allow the 5 upper end thereof to receive a pivot pin 25. A bracket 26 is adapted to be fixedly secured within the wagon body so as to carry a lever 27. This lever 27 is provided with a slot 28 formed in one end portion in which the pivot 10 pin 25 is adapted to extend. This bracket 26 is also provided with a rack 29 which is adapted to be engaged by the lug 30 of the catch 31. By the use of this device when it is desired to lower the saw and at the 15 same time disengage the pinion 16 and the internal gear wheel 17, the pins 15 are first withdrawn. The rack catch may be operated so as to allow the lever 27 to swing upon the bracket 26 thereby causing the arm 20 22 to move downwardly through the slot 24 and in this manner lower the sleeve 9 and shaft 8. Since the yokes 12 are curved the sleeve 9 will move away from the internal gear wheel 17 and thereby cause the pinion 16 25 and internal gear wheel 17 to become disengaged. When this has been accomplished the saw will be down below the wagon bottom 1 as disclosed in Fig. 4 so that the inner surface of the wagon bottom 1 will be sufficiently even.

In order to convey the ice to the saw, the wagon bottom is provided with the tracks 32 upon which the groove rollers 33 are mounted. These groove rollers are connected to and support the rectangular frame 34 which comprises the carriage. This frame 34 is provided at one end with a transverse slot 35 through which the circular saw 7 is adapted to pass as the carriage 40 is moved toward the saw and the ice which is positioned upon the carriage is being cut into the desired sizes. It will also be noted that the saw will be held in its correct central position so as to extend through the slot 45 6 formed in the bottom 1, since the collars 10 ride upon the outer faces of the yokes 12 as clearly disclosed in Fig. 5.

From the foregoing description it will be seen that a simple and efficient means has 50 been produced for cutting the ice carried by the wagon body into the desired quantities and sizes and which is so formed as to be easily shifted to an inoperative position when it is not desired to use the same.

55 I claim:—

1. In a device of the class described the combination with a supporting body, supporting wheels positioned upon said body, a saw carried by said body and extending 60 upwardly through its lower portion, a shaft keyed to said saw, said shaft provided upon its outer end with a pinion, an internal gear wheel fixedly secured to one of said supporting wheels, said internal gear wheel

adapted to rotate said pinion whereby the 65 shaft will rotate said saw for cutting the material within the body, and means for shifting said saw to an inoperative position when desired.

2. In a device of the class described the 70 combination with a supporting body, said body provided with a longitudinal slot in its lower portion, a saw carried by said body and extending through said slot, a shaft keyed to said saw, said shaft provided with 75 a pinion upon its outer end, an internal gear wheel fixedly secured upon one of said supporting wheels, said internal gear wheel adapted to rotate said pinion whereby 80 rotary motion will be imparted to said saw for cutting material within the body, a sleeve positioned upon the outer portion of said shaft whereupon said shaft is journaled, and means for shifting said sleeve to move said saw to an inoperative position. 85

3. In a device of the class described the combination with a supporting body, a plurality of supporting wheels positioned upon said body, said body provided with a slot in its lower portion, a saw passing upwardly 90 through said slot, a shaft keyed to said saw, said shaft provided with a pinion upon its outer end, an internal gear wheel fixedly secured to one of said supporting wheels, said internal gear wheel adapted to engage said 95 pinion whereby rotary motion will be imparted to said saw as said internal gear wheel rotates, a sleeve positioned upon said shaft and provided with collars upon its ends, a plurality of curved yokes fixedly secured to the lower portion of said body, said sleeve and said shaft passing through said yokes, said collars engaging the outer faces of said yokes for holding said sleeve in a central position relative to said yokes, 100 and means for shifting said sleeve and shaft to the lower portion or upper portion of said yokes whereby the saw may be moved to an operable or inoperable position when desired. 105

4. In a device of the class described the combination with a supporting body, supporting wheels positioned upon said body, a circular saw passing through the lower portion of said body, a shaft keyed to said saw, 115 said shaft provided with a pinion upon its outer end, an internal gear wheel fixedly secured to one of said supporting wheels, said internal gear wheel adapted to impart rotary movement to said pinion whereby said 120 saw will be rotated, a sleeve positioned upon said shaft, a plurality of curved yokes fixed upon the lower portion of said body, said sleeve and shaft passing through said curved yokes, means carried upon the ends 125 of said sleeve and engaging the outer faces of said yokes for holding said sleeve and shaft against longitudinal movement, an

arm connected to said sleeve, a lever connected to said arm, said lever being pivotally secured to the inner portion of said body, means for holding said lever in a set position, said lever adapted to allow said sleeve and shaft to be lowered whereby the sleeve and shaft will travel within the curved yokes so as to cause the pinion and gear

wheel to become disengaged when the saw is in an inoperative position. 10

In testimony whereof I hereunto affix my signature in presence of two witnesses.

WALTER F. MOORE.
